UNITED STATES PATENT OFFICE.

SOLOMON SWETZOFF, OF BOSTON, MASSACHUSETTS.

MOLD.

1,245,636.

Specification of Letters Patent.

Patented Nov. 6, 1917.

Application filed July 21, 1916. Serial No. 110,506.

To all whom it may concern:

Be it known that I, SOLOMON SWETZOFF, a citizen of the United States, residing at Boston, in the county of Suffolk and State 5 of Massachusetts, have invented a certain new and useful Improvement in Molds, of which the following is a specification, reference being had to the accompanying drawings.

10 The immediate object of this invention is to provide a simple, inexpensive, and specially convenient, form of mold for use in casting jewelry and, more particularly, for casting finger rings.

15 Heretofore, so far as I am familiar with the art of ring making, it has been quite common to make use of molds made of cuttle-fish bone, a new mold being necessary for each casting, but my present im-

20 provement renders it possible and quite practicable to make a large number of castings from a single mold.

25 My invention is fully illustrated in the annexed drawings, Figure 1 of said drawings being a side elevation of a mold, embodying my present improvements, as constructed for casting a ring having an integral pronged crown, and Fig. 2 is an edge view of the same. Figs. 3 and 4 are inner 30 face views of the two mold-sections adapted for casting a plain ring. In Fig. 5 I have shown end and circumferential views of the core used in producing such a ring.

35 Fig. 6 is a transverse, sectional, view of the mold section of Fig. 3, taken on the line 6—6 of said Fig. 3. In Fig. 7 I have shown an inner face view of a mold section which is specially planned for casting a pronged ring, showing also, in proper relation to the 40 said mold section, a removable mold section for the pronged crown, and Fig. 8 is an inner face view of said removable section.

45 Referring now to these drawings, the numerals 10 and 11 each indicate a mold-section of a mold proper for casting a plain ring, these sections being formed preferably of carbon, the confronting faces of the two sections being chambered in the customary manner, to provide a two-part mold 50 forming in shape to the shape of the ring which it is desired to cast and in the mold thus provided I locate a core 12 formed of carbon, preferably charcoal.

55 The mold and core thus provided, for the production of plain band rings, are practically indestructible. For use in casting

pronged rings I provide a three-part mold, that is to say, I utilize for the ring proper a two-part mold like the one just described excepting that the annular chamber cuts 60 through the lower edge portion of said mold, and I then provide an abutting mold section 13 which is suitably chambered, as at 13^a, to provide a mold for the casting of prongs integral with the ring proper and, 65 because of the novel arrangement and operation of the complete mold, I am able to utilize cuttle-fish bone for the mold section 13 and to use the same repeatedly instead of being compelled to provide a new prong 70 mold for each casting. The carbon mold sections 10 and 11 are vented as at 14 and 15 and they are also provided with the customary gate 17 for use in pouring the molten metal. 75

I will now describe a novel construction of frame-work by means of which the mold sections may be conveniently clamped and supported in proper relation to each other and, by means of which, the mold section 13 80 may be separated from the mold proper without destroying the delicate walls between the individual mold-sections.

Referring now to Figs. 1 and 2, the reference numerals 18 and 19 denote parallel 85 rods located at opposite sides of the main carbon mold sections 10—11 and having in-turned terminals 18^a—19^a which are located between said mold sections and the prong mold section 13, as is best seen in Fig. 1. 90 The other ends of the rods 18—19 are fixedly joined by a plate 20; and slidably mounted upon the said rods is a similar plate 21 that is normally spaced apart from the plate 20 by means of spiral springs 22 95 and 23 mounted on the said rods between the two plates 20—21. The plate 21 is preferably formed with lateral extensions 21^a, 22^a that are adapted to clasp the opposite sides of the carbon mold and thus prevent 100 the accidental separation of the mold sections of said mold and I also provide a band 23^a which surrounds the carbon mold, as well as the rods 18—19, and serves not only as a binder for the mold sections but also 105 as a support and guide for the said rods.

The prong mold section 13 is held in proper relation to the carbon mold by dowel pins and also by a spiral spring 24 whose ends are detachably secured to pins 25 and 110 26 located in the opposite sides of the carbon mold; the said spring being passed

around the mold section 13, under tension, and thus serving to press mold section 13 into close engagement with the carbon mold.

The carbon mold may be used, in the casting of plain rings, without the mold section 13 and without the described wire frame, in which event the two half sections of the carbon mold would be held against separation by the binder 23^a, but, in casting pronged or signet rings, requiring the use of the mold section 13, I prefer to use the said wire frame in which case the pouring of the metal may be through a central opening in plate 21 which registers with the gate in the carbon mold. After the metal has been run and cooled the spring 24 is released when, by holding the carbon mold, and pressing down the plate 20, against the restraining force of the springs 22 and 23, the inturned ends 18^a—19^a operate to force the

mold section 13 straight away from the carbon mold, thus withdrawing the prongs of the casting from the small openings in mold section 13 without breaking, or otherwise injuring, the frail wall between the 25 said openings.

The prong mold section 13 is thus left intact and free to be used again.

Having thus described my invention, I claim as new and wish to secure by Letters 30 Patent:—

In combination with primary mold sections, means for retaining said parts in operative relation to each other, a supplemental prong-mold section, yielding means for clamping said supplemental mold section in position and means for forcing said supplemental mold section away from the primary mold sections. 35

SOLOMON SWETZOFF.
